LIGHTING FIXTURE FOR USE WITH
ELONGATED TUBULAR LAMPS

John S. Walsh, San Francisco, Calif.

Application July 26, 1948, Serial No. 40,707

16 Claims. (Cl. 240—51.11)

1

This invention relates to an improved lighting fixture. More particularly it relates to a lighting fixture for use with tubular or linear types of light sources, such as fluorescent lamps.

This invention solves several previously unsolved problems in connection with luminous indirect fixtures for fluorescent and other linear-type tubular lamps. Although the modern fluorescent lamps have a greater lumen output per watt than any other commercially available light source, their efficiency has been impaired by the lighting fixtures in which they are placed. A typical luminous indirect fixture is a rectangular box of diffusing glass open at the top, and suspended from the ceiling by two or three tubular fixture stems of small cross-section. Inside the box are four 40-watt 48-inch fluorescent lamps mounted horizontally parallel to one another just above the bottom panel of diffusing glass, and the necessary ballasts, in a wiring channel of square or rectangular cross-section. Some fixtures modify the shape by employing semi-cylindrical plastic diffusing panels beneath the tubes instead of the flat glass panels. However, in all of these luminous indirect fixtures, the maximum light intensity is directed upward against that portion of the ceiling immediately over the fixture, and secondarily through the panels to the work area immediately below the fixture. When parallel rows of such fixtures are used the unevenness of the light is seen by the alternation of very bright and very dark areas on the ceiling—caused by a lack of proper light control. The indirect light thus produced gives very poor results in general illumination of a room, both because of the low overall efficiency of the fixtures, and because of the objectionable contrasts in ceiling brightness which preclude comfortable vision.

Another problem heretofore encountered is the great weight of fixtures employed. A typical fixture such as has been described weighs 50 pounds, and constitutes a heavy load to suspend from the ceiling on slender fixture stems, especially in areas subject to earthquakes. They are dangerous and are difficult to install and repair.

Still another problem is that present-day fluorescent luminous indirect fixtures are difficult to clean. If the glass or plastic panels can be removed at all, the process is made difficult by latches, hinges, or other locking devices conventionally employed. If the glass or plastic diffusing panels are fixed, the fixtures must be cleaned in place. Often this must be done by a maintenance man on a ladder with water and soap

2

immediately over a desk or over a heavily-trafficked work area.

One object of this invention is to solve the above problems.

5 Another object is to provide a luminous indirect fluorescent lamp fixture which utilizes maximum light output from the lamps.

Another object of this invention is to provide a lighting fixture for fluorescent lamps which will give an even illumination on the working plane.

Another object is to provide a suspended lighting fixture for fluorescent lamps which will give more even illumination on the ceiling, resulting in a minimum of brightness contrast between the areas directly above and the areas between fixtures.

Another object of the invention is to provide a highly efficient luminous indirect fixture, that is, one in which 90% to 100% of the fixture light output is emitted above a horizontal plane through the fixture center.

Another object of the invention is to provide a luminous indirect fixture having a light shield or baffle for a linear light source, which operates to reduce glare below the fixture and operates at the same time to provide wide-spread upward reflection of light from the lamp.

Another object of the invention is to provide a luminous indirect lighting fixture adapted for use as a single tubular lamp fixture or a multi-lamp fixture by simple assembly of standardized parts.

Another object of the invention is to provide a luminous indirect lighting fixture unit which can be used for single or multi-lamp illumination and in lamp fixtures to be suspended from the ceiling as well as fixtures mounted on the wall.

Another object of the invention is to provide a suspended lighting fixture for fluorescent lamps which is light in weight.

Another object is to provide a luminous indirect lighting fixture for fluorescent lamps with ballasts or transformers, attached directly to the ceiling, rather than suspended on light weight tubular stems.

A further object is to provide an attractive linear type fixture which is easy to clean.

A further object is to provide a fixture with easily removable plastic or glass panels which merely lie in place due to the force of gravity.

Other objects and advantages of the invention will appear from the following description of a preferred embodiment. In accordance with United States Revised Statutes, section 4888, this

embodiment is described in detail but it is not intended to thereby limit the claims.

In the drawings:

Fig. 1 is a view in perspective from below of a fixture embodying the invention; the fixture here shown is a four-lamp ceiling unit;

Fig. 2 is a view in perspective from below of the ceiling detail of the same fixture, with the canopy slid down the stems to show the ballast mounting;

Fig. 3 is a view in vertical cross-section of the fixture shown in Fig. 1;

Fig. 4 is a diagram showing the reflection pattern of the upper lamp on one side of the fixture shown in Fig. 3;

Fig. 5 is a diagram similar to Fig. 4 showing the reflection pattern of the lower lamp;

Fig. 6 is a candle-power distribution curve showing the light distribution of the right hand half of the fixture shown in Fig. 3; the curve represents the intensity of the light emanating from one side of the fixture of Fig. 3, plotted against angle of emanation;

Fig. 7 is a view in vertical cross-section of a modified form of lighting fixture similar to that shown in Fig. 1; the fixture here shown is a two-lamp unit adapted for wall installation;

Fig. 8 is a view in vertical cross-section of another modified type of lighting fixture—a two-lamp unit adapted for suspension from the ceiling;

Fig. 9 is a view in vertical cross-section of another modified type of lighting fixture similar to that shown in Fig. 8—a one-lamp unit adapted for wall installation; and

Fig. 10 is a diagram showing the relation of the reflecting surfaces in Fig. 9 or the lower-left hand portion of the other lamps, to a more complete parabola.

In general the invention comprises a lighting fixture for use with tubular light sources. It includes a frame member, reflecting surfaces supported by the frame member and having an approximately parabolic cross-section with the axis of the parabola inclined upwardly, and a linear lamp supported by the frame member at the focus of the parabola. The fixture also includes a shield or baffle which substantially reduces the direct lighting through the bottom of the fixture and has a reflecting surface which adds further ceiling illumination to that from the main reflectors.

The fixture 10 shown in Figs. 1 and 3 is designed primarily for suspension mounting from a ceiling 11. A flat strap 12 of wrought iron is bolted against the ceiling by toggle bolts 13, and lamp ballasts or transformers 14 are fastened to the strap 12. The ballasts or transformers 14 and the strap 12 are then covered by a canopy 15, which slides up stems 16 and 17. The canopy 15 is secured in place by cylindrical metal collars 18 and 19 whose set screws tighten into the fixture stems 16 and 17. Because the heavy transformers or ballasts 14, etc. are held directly on the ceiling 11, the weight of the fixture 10 itself is correspondingly reduced. When constructed from aluminum and acrylic plastics it weighs only about 30 pounds, and gives over 70% more illumination than a 50 pound prior-art unit.

The fixture 10 as shown generally in Fig. 1 and more specifically in Fig. 3 comprises two identical frame members 20 and 21, on which are mounted four linear fluorescent lamps 22, 23, 24, and 25, and four shields 26, 27, 28, and 29, one for each lamp.

Each of the frame members 20, 21 is preferably extruded, formed or rolled of aluminum, with the outer surface given a specular or mirror-like finish of high reflectance for light control. At the top of the right frame member 20 (Fig. 3), a vertical flange 30 is designed to be joined to a corresponding vertical flange 31 on the left frame member 21 by riveting, bolting, welding, or other means.

Horizontal shoulders, 32, 33 join the flanges 30, 31 to upper parabolic reflecting surfaces 34, 35, respectively. Each parabolic reflector 34, 35 is part of an optical system with the center of its linear light sources 22, 23 at its focal point, and its axis 36, 37 preferably inclined at an angle of approximately 115° above nadir.

Below the upper reflectors 34, 35 there are inclined flat surfaces 40, 41, having openings 42, 43 at intervals corresponding to the lamp length. Into these openings 42, 43, the lampholders 44, 45 of lamps 22, 23 are inserted and fastened to the inner surface of the frame 20, 21 before the bases are joined together. Wires 46 run from the center of the hollow stems 16 and 17 into a channel 47 inside the frames 20, 21 and thence to the lamps 22, 23, 24 and 25.

Below the inclined flat surfaces 40, 41 are the lower reflector surfaces 50, 51, which are also approximately parabolic and are each part of an optical system with the center of the linear light sources 24, 25 at its focal point. The axis 52, 53 of each of these parabolas preferably lies at an angle of approximately 125° above nadir, so that the lower parabolas are somewhat more vertically inclined than the upper parabolas.

Below the lower reflector surfaces 50, 51, the surfaces of the frames 20, 21 are plane and approximately vertical at 54, 55. Into openings 56, 57 at intervals corresponding to the lamp length, lampholders 58, 59 are inserted and fastened in a manner similar to that used with lamp-holders 44, 45 above.

Underneath the surfaces 54, 55, the frame members 20, 21 are inturned at 60, 61 to channels 62, 63. The frames are joined together at these channels 62, 63 by riveting, bolting, welding or other means. Outturned flanges 64, 65 run along the lower edge as a support for the bottom shields 28, 29.

The bottom shields 28, 29 may be opaque reflecting members, but preferably they are translucent panels of glass or plastic. Translucent acrylic resin panels are ideal because of their light weight, their strength, and their light-diffusing and shatterproof qualities. Each panel 28, 29 comprises an incurved central portion 70, 71 of parabolic cross section, an outcurved, inner, almost horizontal supporting portion 72, 73, and an outcurved, upstanding outer portion 74, 75. The inner edges of the reverse-curve portions 70, 71 rest on the lowermost frame flanges 64, 65, and their arching provides support to the panel and helps prevent deformation by cold flow.

The ends of the bottom reflector panels 28, 29 rest on curved supporting strips or flanges 80 of T-section extruded or die cast supporting members 81, or on flanges 82 on the inside surface of end plates 83 which follow the form of the reflector panel, and are joined to the central frame members 20, 21. Fig. 1 shows two pairs of bottom panels 28, 29 supported along their inner edges by the flanges 64, 65, supported at their outside ends on flanges 82 of the plates 83 and at their inside ends by the strips 81. Preferably the panels 28, 29 are held in place solely by gravity and may

be removed for cleaning simply by lifting them off the supporting flanges 80 and 82.

The parabolic portions 70 and 71 are continuations of the same parabolas as the reflectors 50, 51. Their axes 52, 53 are identical, and the lamps 24, 25 are at the focus. Fig. 10 illustrates this fact diagrammatically. The parabola P is interrupted near the vertex V, where the light would mostly be reflected back through the focus F and be absorbed by the lamp 25, but the important side arcs 50, 51 and 70, 71 are there to send the light rays in inclined, parallel paths toward the ceiling. Due to the angle at which the light strikes the surfaces 70, 71, a comparatively small amount is refracted through the panels 28, 29. Most of the light is reflected off with high efficiency. What light does shine through enhances the attractiveness of the fixture and the evenness of the diffused lighting below.

At their outer extremities the surfaces 70, 71 break sharply, arcs 76, 77 of small radius leading into the gentle reverse curve surfaces 74, 75 which serve as shields or baffles to protect the eye from the glare of bare lamps. At their outer edge, the baffle portion terminates in short stiffening beads or flanges 78, 79.

The upper translucent or opaque reflector panels 26, 27, shown in Fig. 3, are cylindrical arcs, i. e., their cross sections are circular arcs. The outer side edges 84 of the panels 26, 27 rest on upper flanges 85 of the end plates 83. The inner side edges 86 rest on curved supporting strips or flanges 87 of T-section extruded or die cast supporting members 88, joined to the central frame members 20, 21. The strips 87 and flanges 85 follow the form of the panels 26, 27. Like the panels 28, 29, the panels are held solely by gravity and are merely lifted off the flanges 85 and 87 when it is desired to remove them.

The lengthwise edges 90, 91 of the panels 26, 27 are bent over and beaded or flanged to give added strength. The inner edges 90 also help prevent slipping by abutting against stop members 92 on the flanges 85 and 87.

The upper reflector panels are generally parallel to the respective axes 52, 53 of the optical system formed by the reflector surfaces 50, 70 and 51, 71. Preferably the axes 52, 53 coincide with the chords of the arcs 26, 27. In this position, the upper reflectors 26, 27 provide the least interference with the light directly radiated from the lamps 24, 25 or reflected from the surfaces 50, 70 and 51, 71.

The main purpose of the upper reflector panels 26, 27 is to shield the eye of the observer from the glare of the upper linear light sources 22, 23. By presenting convex specular surfaces to the lamps 22, 23, the upper reflector panels tend to spread the light reflected by its upper surfaces 94, 95 rather than to concentrate the reflected light on the ceiling 11 over the fixture 10 as it would if its surface were flat or concave. In addition, the arc shape adds appreciably to the strength of the upper reflector panels 28, 29, which are supported only at their ends.

When the electrical circuit is energized the ballasts or transformers 14 produce an inductive kick to establish the arc within the lamps 22, 23, 24, and 25. The lamps then radiate visible energy or light, which travels in straight lines except where reflected by surfaces or refracted through translucent material.

Fig. 4 is a right half section of the lighting fixture 10, showing only the paths of light from the right upper lamp 22. If the tubular lamps

are assumed to be linear light sources, then light is radiated equally in all directions in a plane normal to the lamp from 0° at nadir (directly down) through 180° at zenith and around to nadir at 360°. Fig. 4 shows the light radiation from the upper lamp 22 at approximate 30° intervals. That light radiating directly downward from 0° through about 8°, as shown by the 0° beam 100, strikes the lower lamp 24 and is partially reflected, but largely absorbed. From about 8° through about 42° the light is reflected from the lower reflecting surface 70 to light the under surface of the upper reflector panel 28 or to pass between the panels to the ceiling, as does beam 101 at 30°.

From about 43° through about 100° light rays 102 (60°) and 103 (90°) from the lamp 22 are scattered at wide angles by the convex upper surface 94 of the upper reflecting panel 26. From about 100° through about 188° light rays 104 (120°), 105 (150°), and 106 (180°) from the upper lamp are radiated directly to the ceiling with no loss due to reflections within the fixture. Between about 188° and about 255°, light is reflected by the parabolic surface 34 in a line parallel to the axis 36 of the optical system at 115°. Typical beams are 107 (210°) and 108 (240°). Light from about 255° to about 352°, striking the plane surface 48, is either scattered at wide angles 109 (270°) and 111 (330°), or reflected back into the lamp to be largely absorbed, as at 110 (300°). From about 352° back to 0° the light from the upper lamp strikes the lower lamp and is partially reflected but largely absorbed.

Fig. 5 is similar to Fig. 4 and shows the light radiation from the lower lamp 24 at 30° intervals. That light which radiates directly downward from 0° through about 20° as shown by the 0° beam 120 is reflected by the surface 74 into the area immediately above the upper baffle 26 or on its surface. From about 20° to about 66° the light radiated from the lower lamp 24 is reflected by the near parabolic curve 78 generally along the axes 52 of the optical system at 125°; beam 121 at 30° is typical. Between about 66° and about 95°, light from the lower lamp 24 is reflected to the reverse curve 74 and thence is reflected to the under surface of the upper reflector panel 26, as is the case with beam 122 at 60°, or it directly strikes the curve 74 and then is reflected as before, as is the case with beam 123 at 90°. Between about 94° and about 100° the light which strikes the reverse curve 74 is reflected at wide angles to the ceiling.

From about 100° to about 125° the light reaches the ceiling directly at near horizontal angles to build up the widespread distribution of the fixture at high efficiency, (e. g. beam 124 at 120°). Between about 125° and about 132° radiation from the lower lamp is redirected to the ceiling by the reflector surface 94, much of it at wide angles. Between about 132° and about 172° radiation, the beam such as beam 125 (150°), again reaches the ceiling directly to build up fixture efficiency. From about 172° to about 184° light, such as the beam 126 (180°) from the lower lamp 24 strikes the upper lamp 22 where it is partially redirected, but largely absorbed.

The near parabolic reflector surface 50 reflects light from the lower lamp between about 184° and about 235° largely parallel to the optical system axis 52 at 125°. Beam 127 at 210° is illustrative. Behind the lower lamp from about 235° to about 315° the plane surface 54 scatters the light at wide angles (e. g. beam 128 at 240° and

beam 130 at 300°) or reflects it back into the lamp (e. g. beam 129 at 270°) where it is largely absorbed between about 315° and 0° some of the radiation is subjected to multiple reflections and absorption (e. g. beam 131 at 330°).

Fig. 6 is a candlepower distribution curve, showing the intensity in candlepower for light emanating from the fixture 10, when the lamps 22, 23, 24, and 25 are 69-watt, 3950-lumen, fluorescent tubes and when all four lamps are lighted. The left half of the complete curve is the mirror image of the right half and is therefore omitted. It will be noted from this curve that the candlepower between 45° and 90° in the direct glare zone is a minimum, while the candlepower between 0° and 45°, in the reflected glare zone is also very low. From 0° to about 90° (a 180° arc spread constituting everything below the level of the fixture 10) the candlepower varies from about 250 to about 550. The candlepower between about 90° and about 105° rises sharply to about 1500, and then continues to increase at a slower rate, reaching a peak of 1960 candlepower at 118°. As the curve shows, the maximum candlepower is emitted at a wide angle, so that the ceiling brightness will be relatively even. The candlepower then decreases gradually to approximately 1500 at 160°, and then sharply to 1000 at 180° immediately upward from the fixture. This as Figure 6 shows, the fixture shrouds out most of the light along upwardly inclined paths. This may be contrasted with prior art indirect fixtures, whose maximum candlepower is directly upward to the ceiling over the unit.

When a series of fixtures 10 are suspended about 27" below the ceiling along parallel lines spaced about eight feet apart the brightness midway between each line of fixtures is about half as great as that directly over the fixture—a difference in brightness very difficult to tell with the eye. Prior art fixtures similarly suspended produce typical ceiling brightness directly over the light source as compared to the aforesaid mid-point of from 4 to 1 up to 10 to 1 or more. This malconcentration of light has been one of the big problems in handling fluorescent light.

Fig. 7 shows a modified fixture 150 adapted to be mounted against a vertical surface, such as the wall 151. This fixture 150 actually comprises one half (in this case the left half) of the fixture 10 already described, and for this reason the same numbers are used for the same parts. Screws 152 and 153 through the flange 31 and channel 63 respectively comprise the fastening means to secure the fixture 150 to the wall 151. Ballasts or transformers may be installed within a recess behind the fixture, or remotely. The parts and their operation having already been described in connection with Figs. 1 to 6, this part of the description will not be repeated.

Similarly, the fixture 160 shown by Fig. 8 is identical to the lower half of the fixture 10. The fixture 160 is a two lamp unit for ceiling suspension. The frames 162 and 163 are very similar to the bases 20 and 21, except that there is no upper lamp mount or reflector, and the shoulders 32, 33 join the reflecting surface 50, 51 to the flanges 30, 31. In all other respects the fixture 160 corresponds to the lower half of the fixture 10 and operates according to the description of Fig. 5.

Fig. 9 shows a fixture 170, which is one half of the device of Fig. 8. It is adapted for wall mounting, where the screws 172 and 173 secure it to the wall 171. The ballast or transformer is in-

stalled within a recess behind the fixture or nearby.

Fig. 10 is a diagram of the parabola in Fig. 9, showing that the surface 71 is a continuation of the same parabola as 51. This diagram also shows that the missing vertex of the parabola is unimportant, because the light reflected from that portion would merely go back to the lamp and would be absorbed there. The side arcs are represented by the reflecting surfaces 51, 71, and these do reflect the light toward the ceiling at a wide angle.

As noted already, all of the shields and baffles are held in solely by gravity—in all of the fixtures described. The feature of ease of cleaning is important in fixtures used in commercial buildings and offices. With the present device the baffles 26, 27, 28, and 29 lift out easily and can be removed and replaced without the use of any tools. This allows the device to be kept clean and at maximum efficiency. Also when the baffles are removed the frame members 20, 21 and the lamps 22, 23, 24 and 25 are easily reached for dusting and replacement.

25 I claim:

1. A luminous indirect lighting fixture including in combination a frame member, one or more portions of which comprise reflectors having a parabolic cross section, the axis of said parabola 30 being inclined upwardly; one or more linear light sources supported by said frame member along the foci of said reflectors; and a translucent light shielding means supported by said frame member below said light sources, said means having a 35 substantial portion of its surface parabolic in cross section and having the same foci and axes as the adjacent reflector, so that all but a fraction of the light striking said means is reflected upwardly from said means parallel to the light 40 reflected by its adjacent reflector, the said fraction being refracted through said means to illuminate it.

2. The fixture claimed in claim 1 in which the outer edges of said shielding means are outcurved 45 away from the light sources and are upturned so as to reduce the direct glare from said light sources.

3. A luminous indirect lighting fixture comprising a frame member adapted for support by 50 a wall, a portion of said frame member being formed as a long, rectilinear reflecting surface of parabolic cross section, the axis of the parabola inclining upwardly; a linear light source supported by said frame member below said parabolic reflecting surface and at the focus thereof; and a light shield supported below said light source by said frame member, part of the upper surface of said shield having a parabolic reflecting surface which comprises an arc of the same 55 parabola as the reflecting surface of said frame member, so that the light is reflected up therefrom parallel to the light reflected from said frame member.

4. The fixture claimed in claim 3 in which the 60 outer portion of said light shield is upturned to reduce the direct glare from said light source, and is cylindrically outcurved.

5. A luminous indirect lighting fixture comprising a frame member having two portions, one 65 positioned over the other, each formed as a longitudinal reflecting surface of parabolic cross section with its parabolic axis inclined upwardly the axis of the lower parabolic reflector being inclined more upwardly than the axis of the

upper parabolic reflector; a pair of linear light sources supported by said frame member, each one being held below and at the focus of its adjacent parabolic reflector; and means to substantially reduce the amount of light which emanates from said fixture below the level of said light sources.

6. The fixture in claim 5 in which the light-reducing means comprises a light shield below the lower light source, supported by said base member, a portion of the upper surface of said light shield being parabolic in cross section and a continuation of the parabola of the lower reflecting means.

7. The fixture claimed in claim 6 in which said light shield is translucent, so as to transmit a relatively small amount of refracted light therethrough, most of the light being reflected up by its upper surface.

8. The fixture claimed in claim 6 in which the outer portion of said shield is upturned to extend above the lower light source and is cylindrically outturned.

9. The fixture claimed in claim 6 in which there is an outturned cylindrical-arc baffle supported by said frame, the chord of said arc lying substantially along the axis of the parabola of said lower reflecting surface.

10. A luminous indirect lighting fixture for suspension from a ceiling, comprising a longitudinal central frame member, on each side of which are upper and lower reflecting surfaces of parabolic cross section, with their axes upwardly inclined, the axis of the lower parabolic reflector being inclined more nearly vertically than the axis of the upper reflector; and a plurality of linear light sources held by said frame member at the foci of said reflecting surfaces.

11. A luminous indirect lighting fixture for suspension from a ceiling, comprising a longitudinal central frame member, on each side of which are upper and lower reflecting surfaces of parabolic cross section, with the axes of the parabolas being inclined upwardly; and a plurality of linear light sources held by said base member at the foci of said reflecting surfaces; and baffles supported by said frame beneath the lower light sources for reducing the intensity of light emanating below said fixture, said baffles having a substantial portion of their upper surface parabolic in cross section with the same focus and axis as the lower reflecting surfaces.

12. The fixture claimed in claim 11 in which said baffles are translucent, so as to transmit a

small proportion of the light, most of the light being reflected off the upper surface of said baffles.

13. The fixture claimed in claim 11 in which there is the additional element of an outturned convex baffle supported by said base, the chord connecting the ends of said baffle lying substantially parallel to the axis of said lower reflector.

14. The fixtures claimed in claim 12 in which the outer portion of said baffles are upturned and extend above the horizontal plane of said lower light sources and are cylindrically outcurved.

15. A luminous indirect lighting fixture for suspension from a ceiling comprising suspension rods depending from said ceiling; a central frame member comprising a longitudinal strip on each side of which are an upper reflector and a lower reflector, each having a parabolic cross section whose axis is upwardly inclined; four linear light sources, each held by said frame member below a reflector and at the focus thereof; a lower translucent baffle positioned below said lower light sources and having parts of its surface parabolic with the same focus and axis as said lower reflectors, and being upturned and outcurved at each long edge and terminating above the plane of said lower light sources; and upper translucent baffles each comprising an outcurved cylindrical arc whose chord is positioned along the axis of one of said lower reflectors.

16. The fixture claimed in claim 15 in which the axes of the upper reflectors lie approximately 115° above nadir, and in which the axes of the lower reflectors lie approximately 125° above nadir.
